US0D1047060S

(12) **United States Design Patent** (10) **Patent No.:** **US D1,047,060 S**
(45) **Date of Patent:** **** Oct. 15, 2024**

(54) **BICYCLE RAMP**

(71) Applicant: **Ninja Mountain Bike Performance, LLC**, Klamath Falls, OR (US)

(72) Inventors: **Caedmon Lee O'Neill**, Klamath Falls, OR (US); **Richard Ignazio La China**, Chiloquin, OR (US)

(73) Assignee: **NINJA MOUNTAIN BIKE PERFORMANCE, LLC**, Klamath Falls, OR (US)

(**) Term: **15 Years**

(21) Appl. No.: **29/868,441**

(22) Filed: **Dec. 2, 2022**

(51) LOC (14) Cl. **21-03**

(52) U.S. Cl.

USPC **D21/817**; D21/698; D21/811; D34/32

(58) **Field of Classification Search**

(57) **CLAIM**

The ornamental design for a bicycle ramp, as shown and described.

DESCRIPTION

FIG. 1 is a perspective view of a bicycle ramp according to the claimed design.

FIG. 2 is a front view of the bicycle ramp.

FIG. 3 is a rear view of the bicycle ramp.

FIG. 4 is a right side view of the bicycle ramp.

FIG. 5 is a left side view of the bicycle ramp.

FIG. 6 is a top view of the bicycle ramp.

FIG. 7 is a bottom view of the bicycle ramp; and,

FIG. 8 is a perspective view of the bicycle ramp in a shortened configuration.

The broken lines in the drawings illustrate portions of the bicycle ramp that form no part of the claimed design.

1 Claim, 8 Drawing Sheets
